US0D1071369S

(12) **United States Design Patent** (10) **Patent No.:** **US D1,071,369 S**
(45) **Date of Patent:** **** Apr. 15, 2025**

(54) **ARM CUFF**

(71) Applicant: **Liquilinks LLC**, Houston, TX (US)

(72) Inventor: **Brittany R. Pacsi**, Farmers Branch, TX (US)

(73) Assignee: **Liquilinks LLC**, Houston, TX (US)

(**) Term: **15 Years**

(21) Appl. No.: **29/859,724**

(22) Filed: **Nov. 11, 2022**

(51) LOC (15) Cl. **29-02**

(52) U.S. Cl. **USPC D29/120.1**
